United States Patent

Des. 240,806

Patented Aug. 3, 1976

240,806

CYCLE TRAILER BODY OR THE LIKE

Edward L. Hawes, 405 E. Goulson, Hazel Park, Mich. 48030, and Allen R. Hawes, 453 E. Marshall, and Edward C. Hawes, 2129 Leitch, both of Ferndale, Mich. 48220

Filed Feb. 26, 1973, Ser. No. 335,509

Term of patent 14 years

Int. Cl. D12—10

U.S. Cl. D12—102

FIG. 1 is a left front perspective view of a cycle trailer body or the like showing our new design;

FIG. 2 is a left rear perspective view thereof;

FIG. 3 is a right side elevational view thereof;

FIG. 4 is a bottom plan view thereof; and

FIG. 5 is a rear elevational view thereof.

The broken lines in the drawing are for illustrative purpose only and form no part of the claimed design.

We claim:

The ornamental design for a cycle trailer body or the like, as shown and described.
